GUSTAVE A. BERGSTROM, OF RIDGEWOOD, NEW JERSEY.

ABRASIVE-COVERED MATERIAL AND THE LIKE.

Application filed November 23, 1925. Serial No. 70,743.

My invention relates to abrasive material as exemplified for instance by the conventional emery cloth, sand paper and other devices in which abrasive grains constitute the abrading medium. In practice it has been recognized that material of this class in which the abrasive grains are arranged as continuous abrading surfaces, quickly deteriorate in use; for instance, such continuous abrading surfaces quickly become glazed due to the fact that the spaces between the abrasive grains become clogged up with particles of the material being abraded, whereby the grinding or polishing properties of the abrading surface are destroyed. Attempts have been made to overcome this condition by providing the active surfaces of the material with alternate coated and uncoated portions. In an existing method this result is attained by deflecting a falling sheet of abrasive grains in a manner of strewing said grains upon a sheet in separated rows. This method is unreliable because of the fact that definite control of the falling grains is lacking and no positive precaution is provided to prevent the grains from reaching those parts of the sheet which are intended to remain uncoated.

The object of the present invention is to provide a novel and efficient method whereby an abrasive material is produced, in which the active surface comprises alternate abrasive and non-abrading portions positively defined with respect to each other in a predetermined manner. Other objects will appear from the description hereinafter and the features of novelty will be pointed out in the claim.

In the accompanying drawing, which shows examples of the invention without defining its limits, Fig. 1 is a diagrammatic view illustrating the method in one of its forms and Figs. 2, 3 and 4 are face views of abrasive sheets produced in accordance with the novel method. For the purposes of illustration and description the method has been shown as applied to sheets of the class exemplified by emery cloth and sand paper. It will be understood that this is not intended to define the limits of the invention and further that the novel method is capable of efficient use in connection with the production of any type of abrading material in which abrasive grains are bound together by means of a suitable binding agent.

In carrying out the novel method, under such conditions a coating 10 of glue or other suitable binders is applied in a predetermined manner to a surface of the material, illustrated in the form of a sheet 11 such as paper, cloth and the like, which thus constitutes a backing. For instance, the surface of the sheet may be completely covered with the binder 10 in which case a coating of abrasive grains 12 is applied overall to said binder 10, while the latter is still unhardened so as to completely cover the same. Portions of the combined adhesive 10 and grains 12 are then removed for instance, by scraping, at predetermined points to produce alternate abrasive portions *a* and non-abrading portions *b*. The aforesaid scraping operation may be accomplished for instance by means of a suitable comb 13 reciprocated in any convenient manner; in this way the binder, to a predetermined extent and the abrasive grains are removed simultaneously along a plurality of parallel spaced lines. By properly controlling and guiding the scraping comb 13 the aforesaid lines along which the removal of the material takes place may be straight, undulating, zig-zag or otherwise to produce corresponding lines of spaced abrading strips *a* on the surface of the sheet; it will be understood that the term "undulating lines" as used in the claims is intended to cover any line other than a straight line. Thus the scraping comb may be actuated to produce the results illustrated in Figs. 3 and 4. If desired, the removal of the material may be accomplished by two scraping combs having reciprocating movements, the paths of which intersect each other, and reciprocated in properly timed relation. In this way, a result such as shown by way of example in Fig. 2 is produced upon the backing sheet 11. It will of course be understood that the removal of the material takes place before the binder 10 has set or hardened.

The results set forth above may be also obtained by removing portions of the binder 10 from the sheet 11 before the abrasive grains are applied; in other words in such case a predetermined pattern, in binder, is first produced upon the surface of the material 11. While the binder pattern is still unhardened, the abrasive grains 12 are applied to the material, these grains adhering to the material 11 only along the lines of the binder pattern.

Instead of creating the binder pattern upon the material 11 as above described this pattern may be otherwise produced thereon; for instance, a roller or cylinder 5 on which the pattern appears in relief may be used for applying the binder to the material 11. The abrasive grains 12 may then be applied to the binder pattern in the same way as set forth above and produce the 10 same results.

With the novel method regular and uniform alternations of abrasive and non-abrading surfaces are provided upon the material and definite channels are provided 15 for the exit, from the actual abrading surfaces, of the dust or particles produced by abrasion, regardless of the direction in which the abrasive coated material is used. In this way glazing of the abrading surface 20 is avoided and the life of the material as an abrasive instrumentality is considerably increased. The abrasive grains are arranged in lines which may be continuous or broken and are preferably in parallel spaced relation with each other; the width of the lines 25 of abrasive grains, the style thereof, the dimensions of the pattern and the spaces between lines of abrasive grains may vary in accordance with the purposes for which the abrasive material are to be used. In 30 addition the difference in height between the abrasive portions and the non-abrading portions is not limited but may be varied as seems desirable. Instead of parallel lines 35 of abrasive grains small groups thereof may be produced upon the material in predetermined patterns, the dimensions of the groups of abrasive grains and of the non-abrading portions between groups being dependent upon the use to which the abrasive 40 material is to be put. In any case the abrasive portions or sections, whatever the character thereof may be, are clearly and sharply defined and the non-abrading sections are 45 so arranged as to be incapable of an abrading action in the normal use of the material;

the abrasive grains are fixed upon the material, cloth or other material or upon any other predetermined surface by means of a suitable adhesive or other bond. Furthermore, in all of the forms of the improvement, sand grains or other abrasive grains, either in bands or groups, lie in a keyed, mortised, or wedged relation to one another, thus creating a holding power and adhesion 55 of the sand or other abrasive grains to the material equal to that which is present in surface coated abrasives coated in the ordinary manner. This holding power is materially greater than in the case of abrasive 60 covered sheets or the like in which the sand or other abrasive grains are strewn over the surface; in such case the grains lie in an open arrangement relatively to each other, and are not keyed, mortised or wedged by 65 other grains of sand. In addition to this an abrasive material produced in accordance with my improved method provides definite angles or abrasion which vary as the pattern is varied; these definite patterns may be 70 chosen and easily produced to obtain any desired abrasive angles suitable for varying classes of work.

Various changes in the specific forms described may be made within the scope of 75 the claim.

I claim:

The method of producing abrasive material of the kind described which consists in applying a binder to a surface of the material, applying a covering of abrasive grains to said binder covered surface and then scraping portions of said binder and adhering abrasive grains from said surface simultaneously along a plurality of predetermined spaced parallel lines to produce alternate abrasive strips and non-abrading strips on said surface.

In testimony whereof I have hereunto set my hand.

GUSTAVE A. BERGSTROM.
